APPARATUS FOR SPINNING TUBULAR ARTICLES

Gustave J. Horak, Penn Run, Pa., assignor to
Aluminum Company of America, Pittsburgh,
Pa., a corporation of Pennsylvania

Application July 25, 1940, Serial No. 347,418

20 Claims. (Cl. 113—53)

This invention relates to metal working and more particularly to an improved apparatus for working and shaping tubular and cylindrical blanks to a predetermined configuration and contour by rolling or spinning, and is primarily concerned with the precision spinning of comparatively heavy gauge and thick walled blanks to a preselected contour.

The invention is applicable to the production of a large variety of contoured tubular or cylindrical articles, but it is especially concerned with the manufacture of spun articles having a contour requiring a relatively heavy reduction in the diameter of the original blank, such, for example, as is required in producing containers, metal bottles, shells, and the like having necks and mouth portions of small diameter relative to the diameter of the body portions thereof.

The principal object of the invention is the provision of an improved apparatus for spinning the peripheral wall of a blank to a desired pattern or shape with precision and accuracy, and the finished product reproduced with uniformity of shape and dimensional characteristics without the necessity of employing internal formers or supports.

Another object is to provide an automatic apparatus arranged to produce completely finished articles.

A further object is to provide a metal spinning apparatus applicable to produce, by a series of progressive and recurrent deformative and shaping passes in opposite directions, a relatively great total reduction in the diameter of a blank in accordance with a preselected pattern without materially changing the wall thickness of the blank.

Another object is to provide cam controlled metal working tools for operating upon blanks to reduce them to a shape determined by the cam contour and, in connection therewith, to provide means for translating cam contours into tool movement with precision and accuracy.

Still another object is to provide spinning tool controlling mechanism that is cam actuated under low cam follower pressure and capable of generating high tool working pressures without loss of precision and accuracy, whereby metals requiring high deformative pressures can be readily spun to desired shape.

A still further object is to provide spinning apparatus wherein the work is radially confined and acted upon by at least three spinning tools so arranged that the radial thrust of one tool against the work is counteracted by the

other tools in combination with an automatic power means for simultaneously actuating the tools through equal and identical movements.

Still other objects and purposes of the invention, including novel combinations and simplified and detailed features of the construction and arrangement, will become apparent as the detailed description proceeds, taken in conjunction with the accompanying drawings illustrating a preferred embodiment of the invention, wherein:

Fig. 1 is a side elevational view of a spinning machine;

Fig. 2 is a plan view thereof;

Fig. 3 is a longitudinal sectional elevational view of the driving spindle and work holding chuck, on an enlarged scale;

Fig. 4 is a view on an enlarged scale taken on the line IV—IV of Fig. 2 and showing one of the tool slides in section;

Fig. 5 is a vertical sectional view taken on the line V—V of Fig. 4;

Fig. 6 is a view taken on the line VI—VI of Fig. 5;

Fig. 7 is a view similar to Fig. 4 but with the cover plate and tool slides removed;

Fig. 8 is a view taken on the line VIII—VIII of Fig. 7;

Fig. 9 is a view taken on the line IX—IX of Fig. 7;

Fig. 10 is an enlarged detail view of the cross slide and control valve taken on the line X—X of Fig. 9;

Fig. 11 is an end view of the indexing mechanism disposed at the upper side of the machine as viewed in Fig. 2;

Fig. 12 is a side elevational view thereof partially in section;

Fig. 13 is a view taken on the line XIII—XIII of Fig. 11;

Fig. 14 is a developed view of the centering and locking drum of the indexing mechanism;

Fig. 15 is a view on an enlarged scale taken on the line XV—XV of Fig. 2;

Fig. 16 is a schematic view showing the series of cams of the pattern controlling device arranged in superimposed relation and illustrating the progressive contouring of the cams for controlling the spinning tool movements and imparting progressively the desired shape to the work;

Fig. 17 is a view taken on the line XVII—XVII of Fig. 2 showing the second carriage and its bead forming tool slides;

Fig. 18 is a fragmentary sectional view taken

on the line XVIII—XVIII of Fig. 17, showing one of the tools in operative position;

Fig. 19 is a view taken on the line XIX—XIX of Fig. 18;

Fig. 20 is an enlarged view, partly in section, of a completed container adapted to be produced entirely by spinning operations; and

Fig. 21 is a diagrammatic view illustrating the hydraulic circuits for controlling the operation of the machine.

The art of shaping metal by spinning has long been practiced by both hand and machine methods, but at present such methods have many limitations that render them unsuited for the commercial production, in large quantities, of many forms of products, especially those formed of comparatively heavy gauge material or a metal requiring high deformative pressures, and those wherein the configuration to be imparted to a blank requires that its wall be deeply necked in or constricted relative to the original diameter of the blank. However, I have evolved an improved spinning method wherein heavy gauge material and relatively deep necking in of the wall of a blank can be performed, and the manufacture of containers and the like effected with precision and accuracy. For example, large capacity, narrow mouth containers used in the dairy industry for the handling of milk are required to be formed with a sealing mouth accurately dimensioned for the reception of a closure and also are required to be of uniform wall thickness in order to give adequate strength and durability, and, in general, to be of such form to meet stringent and rigid sanitary requirements. Heretofore, it has been the practice to manufacture such containers by joining separately formed bottom, body, and mouth pieces by soldering or welding, the spinning of such containers not being practical because of the need for employing internal formers or mandrels and the inability to maintain substantially a uniform wall thickness.

In Fig. 20 of the drawings, I show a one-piece container of substantially uniform wall thickness that I am enabled to produce by spinning from a cup-like blank of relatively heavy gauge aluminum alloy having a tubular body closed at one end, and such container reproduced in commercial quantities. The container comprises a body portion 1 of a desired diameter, a tapered or sloping shoulder portion 2, configured as desired, leading from the body 1 to a constricted neck portion 3, and terminating in a beaded mouth 4. It is to be observed that the diameter of the neck opening is greatly reduced relative to the body of the container, thus requiring considerable displacement or deformation of the wall of the blank to produce this reduction. The finished container is produced entirely by spinning operations capable of being carried out by a wide variety and form of apparatus by either automatically or manually manipulated tools, but it is preferably carried out in an improved automatic machine hereinafter described in detail.

In accordance with the present apparatus for producing these containers, the shaping of the body of a blank is first carried out by a series of progressive correlated deformative operations to form the shoulder 2 and the neck 3, after which the reduced mouth is curled back and beaded, the necessary shaping and beading operations to form the completed container being carried out in sequence.

For the purpose of referring to apparatus suitable for carrying out the method, attention is

directed to the mechanism disclosed in Figs. 1 and 2 of the drawings, which will now be referred to without detailed description of the structure shown therein. It will be observed that the structure is essentially a lathe provided with a motor driven chuck head 5 adapted to receive and grip a blank 6 therein. Adjacent the chuck head, and movable longitudinally with respect to the blank, is a carriage 7; and a second carriage 8 is provided at the other end of the machine in lieu of the usual tailstock. Means are provided for effecting traverse of each carriage. The carriages 7 and 8 carry tool slides, each equipped with suitable spinning tools, and the slides and tools of the carriage 7 are movable at right angles to the normal movement of the carriage. The respective tool slides on each carriage are disposed in angular relation about the spinning axis, and, in addition to the radial slides on the carriage 8, it also is provided with a central slide coaxial with the axis of the chuck 5. The carriage 7 is longitudinally movable with relation to a templet that is adapted to be brought into working position with respect to a cross slide carried by the carriage 7. One edge of the templet is configured, and the cross slide cooperates therewith to impart unitary in and out movements to the tool slides and their tools during longitudinal travel of the carriage 7 in conformity with the pattern or contour of the templet. The cam contour is translated into tool movements by means of a cam follower and suitable operating connections connecting each of the tool slides with the cross slide. Preferably, three spinning tools in the form of rollers having a rounded periphery are provided on the carriage 7, and these tools are inter-connected for unitary movement. The wall of the blank is adapted to be progressively brought into final desired configuration, and for this purpose a series of progressively contoured templets is provided and are successively brought into working position one-by-one after each forward or backward movement of the carriage, the contour depth of one cam being so correlated to the contour depth of its preceding cam that the shaping of the blank will be effected in progressive stages of substantially equal increments.

With a blank fixed in the chuck and rotating at proper spinning speed, the carriage 7 is caused to travel from its normal position adjacent the chuck 5 toward the opposite end of the blank. Normally the tools 10 are out of engagement with the periphery of the blank, but at a predetermined point determined by the contour of the first cam or templet, the tools will be moved inwardly simultaneously to engage the periphery of the blank and apply deformative pressure against the same. This pressure is gradually increased and, of course, is of sufficient intensity to indent or force the wall of the blank inwardly and gradually form a groove therein due to the rotary movement of the blank. Concurrently the radial tool movement positively controlled by the first templet during the longitudinal carriage movement will cause the metal to flow inwardly and longitudinally in a spiral curve ahead of the spinning tools. The deformative pressure exerted by the tools 10 being applied preferably at equal angular points around the periphery of the blank effectively maintains the blank constantly in normal spinning position, thereby overcoming any tendency to displace the blank as a unit laterally of the chuck 5, thereby permitting the employment of high pressure when necessary. The length of stroke for the carriage 7 is sufficient to

carry the tools 10 beyond the unsupported end of the blank, and just before the tools reach the end of the blank the deformative pressure exerted thereby is gradually increased so as to cause the end of the blank to move inwardly along a curved line. At the end of this first pass, the wall of the blank is deformed substantially to the shape indicated by the outermost dotted lines in Fig. 1, the amount or depth of such deformation being positively controlled by the templet.

Another cam or templet is then brought into working position and a second or return pass initiated. During this return pass, the wall of the blank is further deformed, but, due to the fact that the carriage is being moved in a reverse direction, the metal is caused to flow in a direction opposite to the direction of flow during the first pass so that the metal is redistributed along the working zone, thereby restoring the wall to substantially its initial thickness. The deformative pressure is gradually lessened as the tool reaches the starting point so as to blend the contour evolved during the second pass into the contour generated by the first pass adjacent the starting point.

These primary shaping passes are repeated as often as are required until the required shape has been imparted to the blank, as indicated by the innermost dotted lines in Fig. 1, the number of passes required therefor and the amount of reduction effected at each pass being dependent upon and coordinated with the gauge and working characteristics of the metal and the total amount of reduction in diameter required to produce a given configuration or contour. The wall of the blank thus can be progressively reduced to the desired shape without liability of creasing or folding the metal ahead of the tools, while the reversals of the direction of the successive spinning passes under uniform tool pressure produce such shape without materially changing the wall thickness of the blank, although the metal will become more dense and somewhat work hardened. However, by varying the tool pressure along a preselected area during successive passes, the wall thickness at such area can be substantially increased or decreased at will, in addition to deforming the wall to the desired shape. Such pressure control, of course, is effected by suitably contouring the successive templets at the proper points.

The speed of travel of the carriage 7 is reduced for the last working pass, and the pressure on the work is maintained constant throughout in order to impart dimensional accuracy to the shoulder and neck portions 2 and 3, and the surface of the metal substantially burnished to eradicate the tool markings occasioned by the prior heavy tool pressure passes, thus imparting a pleasing finished appearance to the blank.

It has been found desirable to increase the tool pressure at the outer end of the blank, as above described, during each forward or odd numbered pass so as to turn the open end of the blank inwardly along curved lines, which facilitates rapid reduction of the wall and re-engagement of the tools with such curved portion during each subsequent return pass, the tools normally being moved past the end of the blank in order to facilitate the bringing of the succeeding templet into working position.

The inner wall of the blank along the area that is to be curled or turned back to form an exterior bead is scalped by any suitable cutting tool so

as to remove any crazed or scratched surface metal that would be liable to cause cracking during the beading operations. The scalping operation preferably is effected at the beginning of the shaping operations and can be manually carried out.

To form the exterior bead, suitable beading, pressing, and trimming tools are carried by the radial slides on the second carriage 8 and, in addition, a curling tool 11 and a neck supporting plug 12 are carried by the central slide thereof. After completing the body spinning operations, the carriage 8 is advanced into working position adjacent the open end of the blank, whereupon the central slide is advanced so that the plug 12 enters the neck opening and the curling tool engages the edge of the neck 3 and turns it outwardly and backwardly. The central slide is then retracted to bring the plug 12 into position underlying the curled portion and successively the curl closing or beading tool, the pressing tool and the trimming tool are actuated in proper order to complete the formation of the beaded mouth 4, the internal diameter of the mouth being perfected and remaining fixed due to the support afforded by the plug.

After removal of the spun container, the point of juncture between the bead and the exterior periphery of the neck may be completely sealed in any suitable manner, as by soldering, to prevent the entry of bacterior or other foreign matter under the bead, thus rendering the container suitable for use in the dairy industry.

The improved automatic apparatus incorporating the process just described will now be described in detail.

As best seen in Fig. 1, the supporting frame work of the machine, which may be of any suitable form, is shown as consisting of a headstock 40 housing 15 and a horizontally extended bed 16 having guideways 17, on which the tool carriages 7 and 8 are mounted for traveling movement.

In the upper end of the housing 15, a hollow spindle shaft 18 is rotatably supported in roller bearings 19 and 20, as shown more clearly in Fig. 3. A V-belt pulley 21 is rotatably mounted on the shaft and is connected with a pulley 22 that is secured to the shaft of an adjustable speed motor 23 by means of a number of driving belts 24, the pulley 21 being adapted to be constantly driven thereby. A pair of friction clutches 25 and 26, preferably of the multiple disc type, are secured to the shaft 18 and each is provided with a ring element 27 connected to the housing 15 and to the hub of the pulley 21, respectively. Clutch 25 serves as a brake, while clutch 26 serves to transmit power from the pulley 21 to the shaft. The clutches are arranged to be actuated selectively by a common shifting fork 28 having connection with a group of slide fingers 29 disposed in circumferential spaced relation (one such finger being shown in Fig. 3) that are adapted at their ends to actuate locking dogs 30 associated with the respective clutches. The shifting fork is connected through suitable linkage 31 with a handle lever 32. With the handle in the position shown in Fig. 1, the brake clutch 25 is engaged and the shaft is held against rotation, while the pulley clutch 26 is disengaged and the pulley is running free on the shaft.

The work holder or chuck 5 is detachably secured to the forward end of the shaft 18 by means of a clamp collar 33. By loosening the collar 33, the chuck can be readily removed and another chuck of a different size substituted when

it is desired to work upon blanks of diameters exceeding the adjustable limits of a given chuck. The blank 6 is inserted into the open face of the chuck and centered and firmly held in spinning position therein, the chuck necessarily being adapted to grip the blank with sufficient force to resist longitudinal movement of the blank under the drag or pull of the spinning tools.

While any suitable chuck may be employed, I prefer to use a hydraulically operated chuck having radially movable clamps 34 that are toggle actuated into and out of clamping position by a longitudinally shiftable operating rod 35 that extends axially through the hollow shaft 18. The rear end of the rod is secured to a piston 36 operating in a rotary cylinder 37 secured to the shaft 18. The cylinder is provided with a tapered plug seated on ground surfaces in a fluid distributor chamber 38 that is provided with axially spaced annular fluid passages cooperating with ports in the plug leading through separate ducts to the opposite ends of the cylinder, as shown in Fig. 3. A spool type reversing valve 39 is incorporated in the distributor block 38 to control flow and exhaust to and from opposite sides of the piston 36 alternately, thereby to actuate or release the chuck. The valve 39 is actuated by a conveniently located lever 40 which is connected through suitable connecting linkage to the stem of the valve.

The first tool carriage 7 comprises a base portion 41 and an upstanding frame or casing 42 encircling the chuck 5, the casing preferably being of channel form in cross section and closed by a cover plate 43. The central portion of the casing and plate is provided with a large diameter bore therethrough arranged coaxially of the blank 6 and the chuck 5. A power cylinder 44 (Fig. 1) is supported within the headstock housing 15 in parallelism with and below the shaft 18, and contains a piston operating therein which is secured to a piston rod 45. The piston rod 45 is secured to the carriage 7, as shown in Figs. 1 and 8. Upon admitting fluid pressure to the head end of the power cylinder by operation of a starting valve 46, the carriage is moved forwardly along the ways 17 until a member or dog 47 on the base of the carriage actuates a reversing valve 48 secured to the bed 16 to cause reverse travel of the carriage. A second dog 49 is provided on the carriage to actuate the valve 48 at the end of the return stroke of the carriage, the automatic control of the carriage being hereinafter more fully described. The dogs 47-49 are secured to plates 50 that are longitudinally adjustable on the carriage base so that by adjusting the plates 50 relative to each other the length of travel of the carriage can be controlled, as required. Also secured to each plate 50 is a cam block 51 for depressing a control valve 52 against the pressure of a self-contained spring each time the reversing valve 48 is actuated, for a purpose to be hereinafter described.

The spinning tools 10 and their actuating mechanism are carried by the carriage 7 and a plurality of such tools arranged in equal angular relation are employed, as shown in Fig. 4. The tools and their slides are identical and each comprises a supporting bracket 54 secured to the plate 43 and provided with slideways, in which a tool slide 55 is mounted. The outer face of the slide is recessed throughout its length to form lateral guides for an adjusting plate 56. An adjusting screw 57 has threaded engagement with the outer end of the plate 56 and is journaled

in a fixed post or block 58 on the outer end of the slide 55. Rotation of the screw by means of a crank 59, or other suitable tool, effects longitudinal adjustment of the plate relative to the slide.

5 The plate 56 carries a tool holder 60, which is bifurcated at its inner end, in which a spinning roller 10 is journaled. Clamping bolts 61, having their heads disposed in a longitudinal recess in the underside of the slide, extend outwardly 10 through elongated slots in the slide 55 and through the plate 56, the innermost bolt also extending through the tool holder 60. The clamping nuts on these bolts, of course, are loosened when it is desired to effect adjustment of the plate 56 on the slide 55. In addition to the innermost bolt 61, the holder 60 is secured to the plate 56 by a stud bolt 62 extending through an arcuate slot in the holder, the said innermost bolt serving as a pivot about which the holder may be 15 turned to position the roller 10 at any desired angular position with respect to the longitudinal axis of the blank 6.

It is apparent that radial adjustment of the tools 10 in accordance with the diameter of the blank is effected by shifting the plates 56 relative to the slides 55 by means of the screws 57 without disturbing the angular adjustment of the tools, and it is unnecessary to change such radial adjustment until it is desired to operate upon 20 blanks of different diameters. The slides 55, of course, are not disturbed by such preliminary adjustment of the tools.

Each slide 55 is provided with a rigidly attached or integral rack bar 64 which is meshed 25 with a gear 65 secured to a suitable shaft 66 that is journaled in the rear wall of the casing 42 and in a bearing bracket 67 disposed within the casing (Figs. 7 and 8). A sprocket wheel 68 is secured to the shaft 66 around which a driving 30 chain 69 extends, the chain when engaged around each of the sprocket wheels forming a triangular loop within the casing 42, as best seen in Fig. 7. The ends of the chain are affixed to attaching blocks 70 and 71 that are secured to a cross slide 35 40 45 50 55 60 65 70 75 72. The block 70 is adjustably mounted so that the chain may be tightened and all slack removed therefrom, whereupon movement of a cross slide in either direction will be instantly transmitted through the chain to rotate the sprockets in unison and to the same degree. Such rotary movement is imparted through the gears 65 to the rack bars and the tool slides caused to reciprocate, thereby moving the spinning tools radially in and out relative to the axis of the blank. It is preferred to use chains of small pitch so that a greater number of sprocket teeth will be engaged by the chain and backlash or looseness eliminated. In this case, the chains preferably are doubled and double sprockets are used so as to 60 permit transmission of sufficient power without overstrain and excessive wear, although a greater number of parallel sprockets and chains can be employed if necessary.

The cross slide 72 is mounted in a slideway 73 in the base 41 of the carriage and is arranged to be reciprocated by a double acting power piston 74 working in a relatively large hydraulic cylinder 75 rigidly secured to the carriage. The piston is normally centrally located in the cylinder so that it is adapted to be moved in either direction. Connected to the piston 74 is a piston rod 76 and a stem 77, each of equal diameter or area and extending oppositely from the piston through suitable packing glands in the ends of the cylinder. 75 The piston rod is connected to an upright angu-

lar post portion 78 on the cross slide 72 to which post the chain attaching block 71 is secured. The piston rod is provided with a reduced end extending through the post and the adjustable chain block 70, the end of the rod being threaded for the reception of a clamping nut 79 and a locking nut 80 (Fig. 9). The block 70 also is secured to the back leg of the angular post 78 by suitable bolts, as best seen in Fig. 9. By this construction the nuts 79 and 80 can be adjusted to move the block 70 toward the block 71, thereby drawing the chain 69 taut and serving to prevent slippage of the block under the pulling forces transmitted therethrough.

Flow of fluid to the opposite ends of the cylinder 75 is controlled by a valve having a valve body 81 mounted on the cross slide 72 for movement therewith (Fig. 10). The valve body is bored for the reception of an axially shiftable control member or valve spool 82 that extends through the ends of the valve body. Along the bore in the valve body 81 a series of five annular ports are formed, the outer or end ports 83 being connected through a passage 84 and constituting exhaust ports, the central port 85 forming a high pressure inlet, and the two intermediate ports constituting outlet ports 86 and 87, respectively. The outlet ports are connected through conduits 88 and 89 (Fig. 7) with the inner or rod end of the cylinder 75 and with the outer or stem end thereof, respectively.

The spool 82 is formed with a pair of cut-off portions 90 that are arranged to control the outlet ports 86 and 87 simultaneously, the width of the portions 90 being just sufficient to cut off flow through the outlet ports. At either side of the portions 90 the spool is of reduced diameter. Thus, with the spool in neutral cut-off or closed position, the reduced portions thereof will be disposed opposite the ports 83 and 85, while the portions 90 will be in position to just close off the outlet ports from communication with the pressure and exhaust ports.

It will be apparent that the valve is in complete hydraulic balance, and so long as the valve spool remains stationary in its neutral position relative to the valve body, no liquid will flow through the outlet ports to the cylinder 75. The conduits 88 and 89 and the cylinder 75 are constantly maintained filled with liquid which is entrapped therein in the neutral position of the valve. Any leakage past the low pressure side of the cut-off portions 90 to exhaust ports 83 is replaced by flow of equal amounts of liquid past the high pressure side of the portions 90. However, upon shifting of the valve spool to the right, for example, (Fig. 10) the ports 86 and 87 will be opened to exhaust and pressure, respectively, so that fluid under pressure will flow through the port 87, through the conduit 89, to the outer end of the cylinder 75. Simultaneously fluid will be exhausted from the inner end of the cylinder through conduit 88 and port 86 to exhaust port 83. Consequently, the power piston will move to the right, thereby moving the slide 72 and the valve body 81 until the ports 86 and 87 again register with the cut-offs 90, whereupon flow ceases and piston travel stops by entrapment of liquid in the cylinder and connecting conduits. Obviously, shifting the valve spool to the left will effect the same cycle of movements but in the opposite direction. Such cross slide movements are imparted to the driving chain 69, and the tool slides are reciprocated thereby through the connections heretofore described.

For shifting the valve spool 82 manually, its inner end is connected to one leg of an angle arm 91 whose other leg is adjustably clamped to a rod 92 that is slidably supported in extensions 5 of the bars 70 and 71. At its other end the rod is provided with a head 93 slidably disposed in a hollow sleeve 94 that extends through a boss 95 on the casing 42 in screw threaded engagement therewith. The sleeve is provided with a handwheel or crank 96, by means of which it may be rotated. With the head 93 of the rod in engagement with the end wall of the sleeve 94, the valve spool 82 is restrained thereby against outward movement under the influence of a loading spring 97 interposed between the end wall of a cap 98 on the inner end of the valve body 81 and a shoulder 99 on the valve spool. Movement of the valve body under the spring pressure is prevented by the liquid trapped in the cylinder 10 75, the spring serving to prevent valve chatter at the point of cut-off. The crank may be utilized to screw the sleeve in or out of the boss 95 and through the rod 92 to shift the valve spool, thus manually controlling the operation of the 15 20 25 spinning tool 10. The sleeve is screwed inwardly to its innermost position when the valve is to be cam controlled so as to allow the rod to slide freely relative to the sleeve.

The outer end of the spool 82 abuts an aligned 30 35 40 push rod or plunger 100 that is slidably supported in a bracket 101 secured to the valve body 81. A light spring 102 interposed between the bracket 101 and a stop or washer on the plunger 100 serves to maintain abutting engagement between the spool and the plunger at all times. A cam follower or roller 103 is carried by the plunger 100 and is held in contact with the configured edge of one of the cams or templets of a rotary 45 50 pattern controlling device 104 by the action of the valve spring 97.

The pattern device 104 is carried by a shaft 105 that is supported at its ends in brackets 106 and 107 in parallelism with the spinning axis of the blank and laterally in fixed spaced relation thereto (Fig. 2). The valve spool 82 and the shaft 105 are disposed with their axes in a common horizontal plane and in right angle relation so that during travel of the carriage 7 the roller 103 will ride on the interposed horizontal templet of the pattern device.

The pattern device 104 comprises a series of elongated templets 108 radially disposed edge-wise about a common axis and secured at their ends in radial slots formed in the inner faces of circular end blocks or plates 109 and 110. The templets are equally spaced and are adapted to be brought into interposed operative position one-by-one by a step-by-step movement of equal increments imparted to the shaft 105 by the operation of suitable indexing mechanism to which the shaft is operatively connected at one end. During indexing movement, the carriage 7 will be stationary and the roller 103 will be positioned against the periphery of either of the end plates 109 or 110. All of the templets of one set are brought successively into working position during one full revolution of the shaft.

The outer edges of the templets, which all together constitute a cooperative series or set, are contoured or configured in accordance with a predetermined pattern or shape which it is desired to impart to the blank, but on successive templets of a set the depth of such desired pattern is progressively increased, as diagrammatically illustrated in Fig. 16, so that there will be

effected a progressive deformation of the wall of the blank into final desired shape by a series of working passes. The number of templets required to make up a given set depends somewhat upon the working characteristics of the metal of the blank, the ratio or amount of deformation required to produce a given shape without collapsing or creasing the wall, the compressive resistance of the material, etc., all of which factors are determinative. Also, the contouring of the successive cams will be coordinated with respect to the shape to be produced, since, if the shape desired in outline has shallow and deep portions, the shallow portions thereof can be completely formed during early working passes and subsequent working passes utilized to complete the formation of the deep portions.

The templets may be made of any suitable material and can be either a fibrous or metallic material because they are subject only to a very low working pressure. It will be seen that the cam follower pressure is that exerted by the spring 97 and tool moving pressures are generated hydraulically. Thus, the cams and the cam follower are not subject to excessive wear, nor is there a possibility of the templets being deflected laterally, since very low cam follower pressures are employed. Consequently, the cam contours are hydraulically translated into corresponding tool movements very accurately and undesirable variations in such translation are eliminated.

Referring to Figs. 11 to 14, inclusive, the indexing mechanism comprises a jack shaft 112 journaled in suitable spaced bearings on the bracket 107 and has an enlarged end 113 formed with a socket therein for the reception of the end of the shaft 105. Driving connection between the two shafts may be established in any suitable manner, as by means of a spline or key, or the socket and end of the shaft 105 may be of non-circular cross section. A drum 114 is secured to the enlarged end of the shaft 112, and encircling the drum is a split brake band 115 carried by a pivoted arm 116. The band 115 carries friction elements or shoes that are pressed against the periphery of the drum under adjustable tension by a spring 117 mounted on an arm carried by ears on the split ends of the band. The friction device is provided to subject the jack shaft to sufficient resistance to prevent free turning and overrunning when the shaft is indexed.

A clutch of the one-way roller type is mounted on the shaft 112, the driving element 118 thereof being adapted to impart rotary movement in one direction only to the driven element 119 thereof, the latter element being fixed to the shaft. Secured to a hub portion 120 of the clutch element 118 is a gear 121 that meshes with a segmental gear 122 that is secured to a rock shaft 123. The rock shaft is supported in suitable bearings on the bracket 107 and carries a depending arm 124 whose lower end is slotted and engages opposite sides of a pin 125.

The pin 125 is carried by a cross head 126 which is slidably supported in guideways 127 formed in the side wall of the bracket 107. At one end the cross head 126 is provided with a tongue 128 having a slightly elongated slot 129 therein through which extends a pin 130 carried by spaced arms of a clevis 131, the tongue 128 lying between the arms of the clevis. The clevis is secured to a piston rod 132 which is connected to a piston working in a cylinder 133 for effecting reciprocation of the cross head and

oscillation of the gear segment 122, the shaft 112 being advanced one step by outward movement of the cross head.

The guideway 127 for the cross head 126 is provided with a cover plate 134 on which is mounted guides 135, slidably supporting a cam bar 136 for movement perpendicular to the movement of the cross head. The cam bar carries on its inner face an inclined double faced cam lug 137 normally positioned in the path of movement of an extended portion of the pin 130. The plate 134 is cut away sufficiently to accommodate the respective movements of the cam lug 137 and the extension of the pin 130.

It will be seen that when the piston of the indexing cylinder moves outwardly, the clevis 131 and the pin 130 will be advanced without moving the cross head due to the lost motion provided by the elongated slot 129. During this free movement, the pin 130 engages the inclined underside of the cam lug 137 and forces the bar 136 upwardly and raises an arm 138 that is secured at one end to a shaft 139 journaled on the bracket 107, the arm 138 being yieldably urged downwardly by a spring 140. The rocking movement thus imparted to the shaft 139 swings an arm 141 that is slidably clamped thereon outwardly and withdraws a tapered centering and locking pin 142 carried on its outer end out of one of an annular series of equally spaced holes in the periphery of a selector drum 143 that is secured to the shaft. Initial release of the drum and the shaft 112 is thus effected as the pin 130 slides under the cam lug 137 and engages the end wall of the slot 129, after which the cross head 126 is moved outwardly and through the pin 125 and arm 124 turns the shaft 123, thereby moving the gear sector 122 and driving the gear 121 in a clockwise direction, as viewed in Fig. 11. The one-way clutch is arranged to transmit power from the driving element 118 to the driven element 119 when rotated clockwise, and thus the shaft 112 and all the elements connected thereto are indexed one step.

As the pin 130 moves past the cam lug 137, the spring 140 moves the arms 138 and 141 in the reverse direction, so that the locking pin 142 bears against the drum 143 for movement into the next hole of the series at the end of the indexing stroke. To terminate the indexing movement, a nose 144 is provided on the outer end of the cross head 126 to engage one of the stepped portions 145 (Fig. 13) of a transverse abutment member 146 that is slidably supported adjacent its ends in suitable guides formed in the bracket 107. The depth of the steps 145 is graduated relative to each other so that by shifting the member 146 longitudinally to position a given step opposite the nose 144 the length of forward travel of the cross head is controlled, the selection of the proper step giving a length of travel sufficient to move the shaft 112 through an angular distance equal to the spacing between the holes in the drum 143 of one annular series thereof. Of course, the number of holes provided in the annular series corresponds to the number of templets 108 provided in the pattern controlling device 104, whereupon at each indexing operation the succeeding templet will be brought into working position and centered in alignment with the path of travel of the valve roller 103 by entry of the pin 142 into the next hole in the drum. The walls of the holes preferably are tapered to facilitate entry of the pin and centering of the templets thereby.

Indexing operations are effected at the end of

each forward and backward travel of the carriage 7. During movement of the carriage the cross head 126 is retracted to the position shown in Fig. 13 by fluid pressure admitted to the rod end of the cylinder 133. During retraction the gear 121 turns idly with respect to the shaft 112 and the pin 130 engages the upper side of the cam lug 137, thereby camming the bar 136 downwardly against the tension of a spring 147, which spring snaps the bar into engagement with the arm 138 after passage of the pin 130. The locking pin 142, therefore, is not disturbed during such restoration of the indexing mechanism. A lug 148 on one side of the sector 122 engages a boss on the bracket 107 and arrests retractive movement of the various parts in completely retracted position, the frictional device 114-115 assuring that the lost motion between the clevis 121 and the cross head 126 is taken up preparatory to the next indexing operation.

The selector drum 143 is provided with a number of sets of an annular series of holes spaced apart axially of the drum, as shown in Figs. 12 and 14. The number of holes in each set and, therefore, their angular spacing are preselected, and it is preferred to use an even number of holes in each set so that the carriage 7 can be reciprocated through a spinning cycle and the cycle initiated and terminated from the same point, preferably with the carriage in its retracted position. Of course, when a pattern device having a greater or lesser number of templets than the one shown is employed, the arm 141 will be shifted along the rock shaft 123 to register the pin 142 thereof with the set of holes in the drum having a number of holes that corresponds with the number of templets of the substituted pattern device.

In order to change the length of stroke of the cross head automatically into conformity with the requirements of the hole spacing of the selected annular set, the arm 141 is provided with a depending finger 150 engaged in a kerf or slot in the upper side of the member 146, and shifting of the arm 141 results also in shifting the abutment 146. The axial spacing between the sets of holes in the drum 143 is the same as the width or spacing of the stepped portions 145 of the abutment 146, whereupon, regardless of which set of holes is selected and the arm 141 moved into registry therewith, the member 146 also will be moved to position the proper step 145 opposite the nose 144 of the cross head 126. For each set of holes having a given spacing the depth of the stepped portion therefor will allow sufficient cross head travel as to effect the required angular movement of the drum 143.

As shown, the drum is provided with six sets of holes, but, of course, the indexing mechanism can be designed to provide for any desired number of sets of holes as desired. Also, the number of holes in each set progressively increases by two, beginning at the right side of the drum. Consequently, the depth of the abutment member increases in steps from its outer end inwardly so that maximum cross head movement is permitted when the selector arm 141 is in registry with the right-hand set of holes.

As before stated, the shaft 105 has driving connection with the socket of the jack shaft, which connection is established merely by inserting the shaft 105 endwise into the socket. At its other end, the shaft 105 slidably extends through its bearing in the bracket 106, which construction facilitates withdrawal of the shaft 105 for removal and replacement of the pattern controlling

device 104 as desired. The pattern device is fixed in operative position against axial movement by suitable stop collars 152, and it has driving connection with the shaft, as by means of a suitable key or the like.

Control cams 153, 154, and 155 are carried by the shaft 105 (Fig. 2), cams 153 and 154 being adapted to actuate directly control valves 156 and 157, respectively, for controlling certain operations, as hereinafter described. Each of the cams is angularly adjustable relative to the shaft, for which purpose they may be secured by bolts 158 (Fig. 15) extending through circumferentially elongated slots in the cam discs and through flanges formed on supporting members 159 that are secured to the shaft 105. The cams 154 and 155 are disposed on opposite sides of the shaft bearing on the bracket 106 so as to secure the shaft 105 against endwise movement (Fig. 2).

As best seen in Figs. 1, 2, and 7, a lever 160 is pivoted at 161 on the bracket 106 and carries a roller 162 at its upper end which is urged toward the periphery of the cam 155 by a spring 163 connected to the lever below the pivot 161, a stop-bar 164 serving to limit movement of the lever in one direction. The lower end of the lever 160 is connected by a link 165 to an arm 166 that is secured to a rod 167 supported along the side of the bed 16, and which carries another arm 168 to the lower end of which is connected one end of a telescoping pull rod that extends across the bed 16. The pull rod comprises a tube section 169 and a headed rod section 170 which is slidable in the tube, a spring 171 interposed between the head of the rod and the opposite end wall of the tube normally maintaining the parts in contracted position.

The outer end of the rod 170 is connected to an arm 172 clamped to the stem of a metering valve 174. The valve 174 is of a well known type and is connected in the hydraulic circuit of the power cylinder 44 to control the rate of flow of fluid therethrough. The valve is initially adjusted, as by means of a handle 175 on the valve stem, to such a rate of flow as to effect a predetermined fast rate of travel for the carriage 7. After adjusting the valve to the desired open position, the clamp for the arm 172 is tightened and thereafter the valve is moved toward its closed position under control of the cam 155. The throw of the lever 160 transmitted through the pull rod is sufficient to effect complete closure of the valve. However, a thumb screw 176 is adjustably disposed in the path of the handle 175 to stop closing movement and the flow through the valve so limited as to impart a predetermined slow speed to the carriage. It is apparent that when the screw is set to limit closure of the valve and is engaged by the handle 175, the spring 171 will be compressed and the tube 169 and rod 170 merely extended to accommodate for the full throw of the lever 160. After the slow speed traverse of the carriage 7, the lobe of the cam 155 is indexed past the roller 162 and the valve 174 is moved to its initial open position by the springs 163 and 171.

Referring now to Figs. 1, 2, and 17 showing the second carriage 8 hereinabove referred to, it is disposed at the rear end of the bed 16 and is movable toward the open end of the blank 6 by a piston connected thereto and working in a cylinder 180. The cylinder 180 is mounted on a centrally disposed slide plate 181 supported on slide-ways at the top of the bed 16. Secured to the underside of the plate 181 is a nut member 182 having screw threaded engagement with a screw

shaft 183 that is journalled at its ends in fixed bearings 184. The screw carries a handwheel 185 by means of which it may be rotated to move the slide plate 181, its cylinder 180, and the carriage 8 as a unit along the bed 16. The cylinder 180 and its piston are provided to advance the carriage 8 into operative position adjacent the open end of the blank 6 by movement of the piston from the rear end of the cylinder to the other end thereof, the beading tools disposed at the front face of the carriage thereby being properly located with respect to the open end of the blank. Initial adjustment of the carriage to accommodate blanks of a given length is effected by manual operation of the handwheel 185, and this adjustment need not be changed until blanks of a different length are to be operated upon.

The coaxial slide on the carriage 8 comprises a non-rotatable slide bar 186 having the plug 12 rotatably mounted thereon in position to enter the neck opening. The plug 12 is provided with a beveled leading edge to facilitate entry thereof, the diameter of the plug corresponding to the inside diameter of the neck 3. The other end of the bar 186 is connected to a piston working in the cylinder 187 by means of which the bar is reciprocated relative to the carriage. Behind the plug, two diametrically opposed curling rolls 11 are disposed to engage the edge of the neck wall, the periphery of the rolls being suitably shaped to curl the neck wall outwardly and backwardly during forward movement of the slide 186. Each roller is journalled in a block 188 that is supported for radial adjustment on a guide plate 189 secured to an annular flange 190 integral with the bar 186. After curling the neck wall, the slide 186 is retracted by the piston in the cylinder 187, in which retracted position the flange 190 abuts the face of the carriage 8 and the plug 12 will be in substantially the neck supporting position shown in Fig. 18. The curling rolls 11 and their supports will not, therefore, interfere with the subsequent operation of the radial beading tools that are carried by radial tool slides on the face of the carriage.

The tool slides are substantially similar to the tool slides on the carriage 7, but their supporting brackets 191 are U-shaped to overlie operating cylinders 192 supported in suitable recesses in the face of the upright portion of the carriage, as shown more clearly in Figs. 18 and 19. The piston in each cylinder 192 is connected to a depending lug 193 on the underside of the slide 194 on which slide a bracket 195 is adjustably mounted. A tool holder 196 is secured to the bracket 195 by means of clamping bolts extending through elongated slots in an upstanding portion of the bracket, by which means a tool 197 journalled in the inner end of the holder can be adjusted to desired perpendicular or angular position with respect to the longitudinal axis of the blank. One of the slides 194 carries a suitable knife 198 for trimming the beaded edge of the blank, and the other slides carry suitable bead closing and pressing rollers, respectively. A stop block 199 is provided to limit the inward movement of the knife slide, the other slides being moved the full length of the piston stroke.

Each slide 194 carries a cam bar 200 for actuating a valve 201 associated therewith for initiating the operation of the slide successive thereto. Preferably the tools are so arranged around the periphery of the blank that the beading and trimming operations are performed sequentially by operation of substantially diametrically oppo-

site tools so as to eliminate any possibility of interference with each other. A valve 202 (Fig. 2) is associated with the central slide 186, and this valve is arranged to be actuated during retraction of the slide by a cam 203 pivotally mounted on a plate 204 that is secured to the bar 186, the cam being spring biased against a stop 205 on the plate 204. During advance of the slide 186 the cam 203 is turned away from the stop 205 until it can be snapped past the valve stem by the biasing spring, but during retractive movement, the stop 205 prevents such turning and the cam, therefore, depresses the valve to initiate the next bead forming operation.

While the two carriages 7 and 8 and the indexing mechanism may be actuated by any suitable means and their movements correlated with respect to each other by hand control or suitable mechanical control mechanism, I prefer to employ a hydraulic control system therefor in the interest of simplicity and economy of operation. The operation of the machine in a manner to carry out the process as heretofore described for producing completely spun receptacles or containers of substantially uniform wall thickness will now be described in conjunction with the hydraulic control system, as shown diagrammatically in Fig. 21. The system is arranged to effect automatic operation of the first carriage 7 and its tools to spin the body of the blank to the desired shape by repeated working passes effected in opposite directions, the indexing mechanism being indexed one step at the end of each traverse of the carriage. Thereafter the beaded mouth is formed by the automatic sequential operation of the beading tools of the second carriage.

Referring now to Fig. 21, high pressure operating fluid, preferably oil or other inelastic fluid, is supplied from a suitable source to a pressure conduit 206 which is connected to the inlet ports of the various control valves. A common discharge or exhaust conduit 207 is connected to the exhaust ports of such valves for returning liquid to a suitable tank or sump for reuse. A separate source of high pressure fluid is supplied to a conduit 208 that is connected to the inlet port of a transfer valve 209 for supplying operating fluid of constant pressure to the inlet port 85 of the cross slide valve 81-82. It is essential to provide this separate source of fluid for actuating the piston 74 in the cylinder 75 in order that movement of the cross slide 72 and the tools 10 will not be affected by fluctuations in fluid pressure. The valve 209 is a manually operated four-way spool valve, and normally its spool is in its left-hand position with the inlet port open to an outlet port 210 and with its exhaust port open to an outlet port 211. The port 210 is connected to the inlet port 85 and also to the rod end of the cylinder 180. The outlet 211 is connected to the head end of the cylinder 180. Thus, fluid pressure is supplied to the valve 81-82 for actuating the cross slide 72 and also for maintaining the carriage 8 in its retracted position during operation of the carriage 7.

For the purpose of controlling the advancing speed of the carriage 7 and maintaining it in retracted position, fluid pressure is applied constantly to the rod end of the power cylinder 44. This pressure is supplied from the conduit 206 through the metering valve 174 whose outlet 212 is connected directly to the rod end of the cylinder 44. The outlet 212 is also connected to one of the spool controlled pressure ports 213 of the

cam actuated valve 156, the other pressure port being connected to the inlet port of a hydraulically actuated four-way spool valve 214. The valve 156 also is provided with a pair of exhaust ports 215 that are connected to the conduit 207 and the exhaust port of the valve 214, respectively. The valve 156 is provided with a spring for moving the spool 216 into its extended position, the spool being held in depressed position by the cam 153, as shown during forward travel of the carriage 7. In this position of the spool the pressure ports 213 are open but the exhaust ports 215 are blocked. Fluid pressure is thus supplied from the conduit 206 through the metering valve 174, through the pressure ports 213 of the valve 156, to the inlet port of the valve 214, but the spool thereof is in its position blocking flow from the inlet port to outlet port 217 which is now open to the exhaust port. The outlet port 217 is connected to the head or rear end of the power cylinder 44.

Actuation of the valve 214 is controlled by the four-way reversing valve 48 whose outlets F and R are connected to the opposite ends of the valve 214 to shift the spool alternately in opposite directions. In the retracted position of the carriage 7 the outlet port R is open to the exhaust port, while the outlet F is open to the inlet port which is connected to the outlet port 218 of the starting valve 46. Valve 46 also is of the four-way spool type whose spool is manually shifted in one direction into its starting position and hydraulically shifted in the other direction into its off position.

With the carriages 7 and 8 retracted (Fig. 1), a cup-like blank is inserted into the stationary chuck head 5 and the lever 40 depressed to actuate the valve 39, whereupon the fluid pressure connections leading to opposite ends of the rotary cylinder 37 are reversed and the piston 36 moved therein to shift the rod 35 and actuate the centering and clamping members in the chuck head into gripping engagement with the blank adjacent its bottom wall. The lever 32 is then moved to its running position whereby the clutch 25 is disengaged and the clutch 26 engaged and the blank rotated, the spinning speed of the blank being regulated as desired by adjustment of the motor 23. It will be seen that the cross slide roller 103 engages the periphery of the end plate 110 of the pattern controlling device 104, and the spinning rollers 10 are thereby held out of engagement with the side wall of the blank. Also, the first templet 108 is in interposed working position for movement of the roller 103 along its contoured edge.

The starting valve 46 is then manually actuated to shift its spool to the left to initiate the automatic cycle of operation for spinning the body of the blank to the desired shape. Shifting of the valve spool results in supplying operating pressure from the conduit 206 to the inlet port of the reversing valve 48 and thence through the port F to the right hand end of the pilot valve 214, whereupon the spool thereof is shifted to the left to block the exhaust port and to establish communication between the inlet port and the outlet 217. Fluid pressure is thus admitted to the head end of the cylinder 44 behind the piston therein in opposition to the pressure constantly applied at the rod end of the cylinder. Due to the presence of the piston rod 45, the area of the piston at the head side is greater than its area at the rod side, and, therefore, the carriage moves forwardly with respect to the longitudinally fixed blank 6 and the pattern con-

trolling device 104. However, the area of the piston rod is so selected as to provide a 2 to 1 ratio in piston areas, whereupon it will be apparent that advancing and retracting movements of the carriage will be effected at the same rate by reason of the manner of admitting fluid to the opposite ends of the cylinder.

Obviously, during movement of the carriage 7 longitudinally of the blank 6 and the pattern device 104 with the roller 103 riding on the contoured edge of the first templet 108, the valve spool 82 will be shifted axially in and out relative to the valve body 81 in accordance with the elevations and depressions present on the templet. As heretofore described, whenever the valve spool 82 is shifted relative to the valve body 81, the flow of fluid pressure to and from opposite ends of the cylinder 75 is controlled at the ports 86 and 87, the piston 74, the cross slide 72, and the valve body 81 moving as a unit in the direction of movement of the spool 82. In other words, the valve body is caused to follow substantially instantaneously the movements of the valve spool in an endeavor to bring the ports 86 and 87 into registry with the cut-off portions 90 of the spool.

The movements of the cross slide are transmitted through the chains 69 to the sprockets 68 and their shafts 66, and such movements are imparted through the gears 65 and rack bars 64 to 30 reciprocate the tool slides and their tools 10 simultaneously, the extent of movement of the cross slide and the tools 10 being substantially equal. In this manner the contour of the cam is translated into tool movements with precision and accuracy and at any desired operating pressure independently of the pressure exerted against the templet. Thus, very light templets of any suitable material may be employed without introducing a characteristic which might tend 40 to impair the accuracy of the tool movements.

Referring to Fig. 16, as the carriage 7 travels between the points indicated by the letter X, the roller 103 passes off the end plate 110 onto the contoured edge of the templet 108 which is gradually sloped inwardly. As the roller moves along the sloping portion of the templet, the spring 97 causes the valve spool 82 to shift outwardly relative to the body 81, and this movement is transmitted to the spinning tools 10 by movement of the cross slide. The tools 10, therefore, are brought into engagement with the outer surface of the wall of the blank at the desired point behind the open end of the blank. As the carriage moves between the points indicated by the letter 55 Y, further movement of the roller 103 is effected and, consequently, commensurate movement is hydraulically imparted to the spinning tools 10. The wall of the blank is rolled inwardly under the hydraulically applied tools pressure and displaced longitudinally in a spiral direction. The amount of "bite" or reduction in diameter taken during the first working pass, and also during subsequent working passes, is coordinated with the working characteristics of the metal and preferably is such as not to cause creasing or folding of the annular wall at points ahead of the spinning tools. As the tools approach the outer end of the blank, the contour of the templet is such that the tools are forced inwardly to cause the end of the blank to be turned inwardly along an arcuate line. Thereafter, the carriage is moved between the points indicated by the letter Z to carry the tools beyond the end of the blank and move the roller 103 onto the periphery of the end plate 109. In order to facilitate indexing opera-

tions wherein the end plate 109 is rotated relative to the roller 103, the diameter of the plate 109 is made equal to a mean diameter that is equal to approximately one-half the difference between the maximum and minimum diameters of the blank between its unreduced body portion and the reduced neck portion 3 thereof.

Forward movement of the carriage is terminated when the dog 47 actuates the valve 48 to its other position to open the inlet and exhaust ports thereof to the ports R and F, respectively. Thus, fluid pressure is admitted to the left-hand end of the valve 214, and its spool is shifted to the right to block the inlet port thereof and open the port 217 to the exhaust port. However, the carriage does not begin to retract immediately because exhaust from the rear end of the cylinder is prevented by the valve 156 which maintains the exhaust ports 215 closed until after completion of an indexing operation. During advancing movement of the carriage the forward cam block 51 is moved past the indexing valve 52, and its spool is extended by the spring contained therein to reverse the fluid pressure connections to the opposite ends of the indexing cylinder 133, whereupon the cross slide 126 is retracted and the indexing mechanism thereby prepared for an indexing operation.

Substantially simultaneously with the operation of the reversing valve 48, the rearmost cam block 51 depresses the spool of the valve 52, thereupon admitting fluid pressure to the head end of the cylinder 133. Thereby the indexing mechanism is actuated in the manner heretofore described to move the shaft 105 and pattern device 104 one step to bring the next templet into interposed working position, the templet being centered and locked in this position by entry of the locking pin 142 into the hole in the locking drum 143. As the shaft 105 is turned, the cam 153 moves past the stem of the valve 156 and presents thereto a depressed portion which permits the spring in the valve to move the spool 216 into position to block the pressure ports 213 and open the exhaust ports 215. Exhaust of fluid pressure from the rear end of the cylinder 44 is thereby permitted, and the constantly applied fluid pressure at the front end of this cylinder causes the piston to be moved rearwardly and the carriage is retracted thereby.

During the retractive movement the rollers 10 are brought into engagement with the inturned outer end of the blank and the blank subjected to a second shaping operation. But in this pass the metal is caused to flow longitudinally in the reverse direction. The metal is thereby redistributed along the working zone and the gauge or thickness of the wall of the blank maintained substantially uniform. As the tools near the starting point of the first pass, the cam contour is such as to effect lessening of the deformative pressure so as to blend the second pass contour into the contour of the first pass. Also, during this retractive movement, the indexing valve 52 is extended to restore the indexing mechanism into position for another indexing operation.

The retractive movement is terminated when the dog 49 and cam 51 actuate the reversing valve 48 and the indexing valve 52, respectively, the spool of the valve 214 being shifted into its left-hand position.

The shaft 105 is moved one step to bring the next cam or templet into working position and the cam 153 thereon depresses the valve 156 to initiate another forward movement of the car-

riage. This inter-related indexing and carriage traverse movement is carried out until all of the templets of the pattern controlling device 104 have been successively brought into working position and their contours translated into radial tool movements to work the blank into the desired final contour.

Upon indexing of the last shaping templet into working position, the cam 155 actuates the lever 160, and through the telescopic pull rod 169—170 actuates the metering valve 174 for slow speed operation of the carriage, as heretofore described, whereupon during this final shaping pass the carriage is moved at a slow rate of speed and the tool markings on the work substantially eliminated due to the imposition of substantially uniform pressure throughout the entire length of the worked or shaped portion of the blank. This last finishing pass also results in imparting exact shape to the blank with extreme dimensional accuracy. The final working pass ends with the carriage 7 in advanced position and the indexing mechanism is actuated to bring the last templet into working position. The shape of this last templet is such that the rollers 10 are maintained out of engagement with the shaped blank during retraction of the carriage.

The indexing step preceding the final retractive stroke of the carriage moves the cam 155 out of engagement with the lever 160, thereby permitting the metering valve 174 to move to its open position. The indexing step also results in operation of the valve 157 by the cam 154, thereby closing the exhaust circuit through the valve and opening the inlet port 220 to the outlet port thereof. The outlet port is connected to the left-hand end of the starting valve 46, while the inlet port 220 is connected to the outlet of the indexing valve 52 in series with the circuit leading to the rod end of the cylinder 133.

During final movement of the carriage to retracted position, the spool of the valve 52, of course, is permitted to move to its extended position, whereupon fluid pressure is admitted to the rod end of the cylinder 133 to retract the indexing mechanism and also supply pressure through the open ports of the valve 157 to move the spool of the starting valve 46 to the right into its normal off position. As a result of this operation, it will be seen that fluid pressure to the outlet 218 is blocked and that this port is opened to exhaust. Thus, the supply of fluid pressure to the inlet port of the reversing valve 48 is interrupted. Consequently, when the carriage again actuates the reversing valve 48 at the end of its retractive stroke, there will be no pressure supplied to shift the spool of the valve 214, and this valve remains in position blocking pressure flow to the rear end of the cylinder 44 so that the carriage will be retained in its retracted position. However, the indexing valve 52 is moved to depressed position, whereupon fluid pressure is admitted to the outer end of the cylinder 133 and the indexing mechanism actuated to move the first templet of the pattern controlling device 104 into working position. The indexing movement also results in depression of the spool 216 by the cam 153, thereby to open the pressure ports 213 and to close the exhaust ports 215, thus preparing the hydraulic system for a repeated cycle of operations.

In order to form the bead on the mouth of the container, the transfer valve 209 is manually actuated to supply pressure to the outlet 211 and to connect the outlet 210 to exhaust. This results

in removing pressure from the inlet port 85 of the cross slide valve, and also effects advancement of the carriage 8 by admitting fluid pressure to the head end of the cylinder 180 and connecting the rod end thereof to the exhaust line 207. Fluid pressure from the outlet 211 is also supplied to a series of metering valves 221, 222, 223, and 224 in the circuit of each of the slides on the carriage 8 for individually controlling the speed of operation thereof. This pressure also is supplied to the inlet ports of various of the control valves associated with each tool slide.

With the carriage 8 in advanced position, the slide carrying the trimming tool 198 is moved inwardly into engagement with the outer edge of the neck portion of the blank momentarily to trim the neck and form an inclined edge thereon. The trimming operation is effected by manually operating a valve 225 to supply fluid pressure through the valve 221 to the right-hand end of a valve 226, thereby shifting its spool to the left, whereupon fluid pressure from the metering valve 221 is admitted to the head end of the cylinder associated with the knife slide. The knife slide, therefore, moves inwardly to engage the blank with the trimming tool 198, inward movement of the slide being limited by the stop 199. The cam 200, associated with the knife slide, is arranged to actuate the impulse valve 201 to initiate actuation of the next tool slide.

A valve 228 of a sequential by-pass type well known in the art is interposed in the circuit leading from the valve 226 to the head end of the knife slide cylinder. When the knife slide engages the stop 199, pressure in the sequence valve builds up to a point sufficient to actuate a spring pressed by-pass that is incorporated therein to permit pressure fluid to flow to the left-hand end of the valve 225 to shift its spool to the right into normal off position. This results in reversing the fluid connections and supplies pressure to the left-hand end of valve 226 and its spool is moved to the right to reverse the connections to the opposite ends of the knife slide cylinder. This results in supplying pressure to the rod end of this cylinder, while its other end is connected to the exhaust line, whereupon the knife slide is retracted.

It will be apparent that due to the rapid rate of rotation of the blank, the knife need be maintained in contact with the blank only momentarily. Thus, substantially simultaneously with the initiation of the reversing impulse at the sequence valve 228, a pressure impulse can be transmitted through the valve 201 to initiate the operation of the next tool slide, and advancing movement of such successive slide effected during retractive movement of the preceding tool slide.

Associated with each tool slide is a group of valves 230, 231, and 232 corresponding to the valves 225, 226, and 228 except that valve 230 is actuated in both directions hydraulically, and the operation of each group of valves is adapted to be initiated by the preceding impulse valve 201. Thus, when the valve 201 associated with the knife slide is depressed by its cam 200, a pressure impulse is transmitted therethrough to shift the spool of the pilot valve 230 of the group of valves associated with the central slide 186. In turn, the main control valve 231 is actuated and fluid pressure supplied past the sequential valve 232 to the rear or head end of the cylinder 187. The central slide 186 is advanced and the plug 12 forced into the neck opening, and the curling

tool 11 is pressed against the edge of the neck wall and curls it outwardly and backwardly. Due to the functioning of the pivoted cam 203, associated with the central slide 186, the impulse valve 202 is actuated upon the retractive movement of the central slide, which retraction is effected upon operation of the sequence valve 232 and the operation of the valves 230 and 231 to reverse their fluid connections, respectively, and cause retractive movement.

Upon depression of the valve 202, the operation of the group of valves associated with the next slide is initiated. This slide may carry a bead closing tool to bend the open end of the curled back portion inwardly into engagement with the wall of the neck. The operation of the succeeding slide is effected in the same manner and in proper sequence. This slide carries a pressing tool 197 to complete the closure of the bead. At the completion of the beading operations, the operator again actuates the transfer valve 209, thereby causing retraction of the carriage 8 and again applying pressure to the inlet port 85.

Only so many of the radial tool slides and their tools as are necessary to effect formation of the bead need be employed, and, of course, the curling tools 11 may be dispensed with and other tools substituted if it is desired to form mouth portions of other shapes.

It will be apparent that the forcing of the plug 11 into the neck opening not only results in affording support to the neck wall during formation of the bead thereon, but will assure the formation of a truly circular mouth of a diameter corresponding to the diameter of the cylindrical portion of the plug.

While I have shown only one shape that may be imparted to an article, it, of course, will be apparent that any other desired shape may be readily imparted to a blank merely by providing a pattern controlling device having its templets properly contoured. The number of templets employed for a given pattern device is, of course, predicated upon the amount of reduction that is to be made in the diameter of the blank, together with the working characteristics of the material, and in all cases the rate of linear movement of the carriage and the spinning rate will be controlled in accordance with these factors. Also, it is to be understood that the shaping of a blank can be effected at any desired portion along its length or along substantially its entire length in the production of many shapes of articles or the ornamentation thereof, and, furthermore, that regardless of the size and shape of the article to be produced, duplication of such articles of identical shape and uniformity of dimensional characteristics can be effected. The production of shaped articles of such characteristics from blanks composed of material having a high compressive resistance to deformative pressures is possible with precision and accuracy due to the improved mode of generating and controlling high working pressures and the shaping of the blank under a series of progressive shaping operations.

I have illustrated and described a present preferred embodiment of the invention, but it will be understood that the same is not limited thereto but may be otherwise embodied or practiced within the scope of the appended claims.

I claim:

1. In a metal spinning machine, the combination with a spinning tool, of means for imparting feeding movements thereto in directions extending lengthwise of the wall of a blank to be acted

upon thereby, and operating mechanism movable lengthwise with the tool for imparting feeding movements thereto at will in directions extending crosswise of said wall, said mechanism comprising fluid pressure actuated means for moving the tool, valve means for controlling the operation of said pressure actuated means, a movable control member associated with said valve means and selectively operable in opposite directions from a neutral position with respect thereto for effecting fluid flow through said valve means and actuation of said pressure actuating means in a corresponding direction, and means movable in unison with said pressure actuated means for moving said valve means in the direction of movement of said member until fluid flow is interrupted.

2. In a metal spinning machine, the combination with a spinning tool, of means for imparting feeding movements thereto in directions extending lengthwise of the wall of a blank to be acted upon thereby, fluid pressure actuated means operatively connected to said tool for moving the same transversely of said wall, valve means for controlling the operation of said pressure actuated means, a movable control member associated with said valve means and selectively operable in opposite directions from a neutral position with respect thereto for effecting fluid flow through said valve means and actuation of said pressure actuating means in a corresponding direction, means movable in unison with said pressure actuated means for moving said valve means in the direction of movement of said member until fluid flow is interrupted, and cam means operable during the said lengthwise movement of the tool for imparting predetermined control movements to said control member, whereby corresponding transverse feeding movements are imparted to said tool.

3. In a metal spinning machine, the combination with a spinning tool, of means for imparting feeding movements thereto in directions extending lengthwise of the wall of a blank to be acted upon thereby, an operating mechanism movable lengthwise with the tool for moving said tool transversely of said wall, said mechanism comprising fluid pressure actuated means connected to the tool for moving the same, valve means for controlling the operation of said fluid pressure actuated means, a movable control member associated with said valve means and selectively operable in opposite directions from a neutral position with respect thereto for effecting fluid flow through said valve means and actuation of said pressure actuated means in a corresponding direction, means connecting said pressure actuated means to said valve means for bodily moving the same in the direction of movement of said member until fluid flow is interrupted, an elongated templet having a contoured edge in fixed position for movement of said control member therealong during lengthwise movement of said tool, and means for yieldably pressing the control member against said edge, whereby said member is moved relative to said valve means in conformity with the contour of said edge and corresponding transverse movements are imparted to said tool.

4. In apparatus for spinning tubular blanks, the combination with a chuck for receiving and gripping a blank therein, means for rotating the chuck and the blank, a tool carriage, a spinning tool mounted on the carriage for radial movements relative to the wall of the blank, means for advancing and retracting the carriage in di-

rections parallel to the axis of said blank, a pattern device arranged parallel to said axis in longitudinally fixed position with respect to the movement of the carriage, said device including a series of elongated and progressively contoured templets adapted to be moved into operating position one-by-one, means operatively connected to said tool and cooperating with said pattern device for translating the contours of said templets thereof into radial tool movements during traverse of the carriage along said blank, and means for moving each of said templets successively into operating position for translation of its contour into tool movements by said last named means, to impart a corresponding contour to said wall.

5. In apparatus for spinning tubular blanks, the combination with a chuck for receiving and gripping a blank therein, means for rotating the chuck and the blank, a tool carriage, a spinning tool carried by the carriage and mounted thereon for radial movements relative to the wall of the blank, means for advancing and retracting the carriage in directions parallel to the axis of said blank, a pattern device arranged parallel to said axis in longitudinally fixed position with respect to the movement of the carriage, said device including a series of elongated and progressively contoured templets adapted to be moved into operating position one-by-one, means operatively connected to said tool and cooperating with said pattern device for translating the contours of said templets thereof into radial tool movements during traverse of the carriage along said blank, means for moving each of said templets successively into operating position for translation of its contour into tool movements by said last named means, to impart a corresponding contour to said wall, said templets being moved into operating position upon termination of each traverse of said carriage.

6. In a metal spinning machine, the combination with a reciprocable carriage and a spinning tool mounted thereon for feeding movements crosswise of the path of travel thereof, of hydraulically-actuated piston and cylinder means for imparting said feeding movements to said tool, said cylinder means being fixed to the carriage and said piston means being movable therein in opposite directions, means connecting said piston means to said tool for moving said tool in conformity with the movement of said piston means, a control valve movably supported on the carriage and comprising a valve body having outlet ports, an axially shiftable valve spool in said body and cooperating with said ports for controlling fluid flow therethrough, conduits connecting said outlet ports to opposite ends of said cylinder means, said spool being selectively operable in opposite directions with respect to said ports for simultaneously effecting pressure and exhaust flow therethrough and actuation of said piston means in a corresponding direction, means operatively connecting said valve body to said piston means for movement bodily therewith in the direction of movement of said spool until fluid flow is cut off, a spring for loading said valve, and means for shifting said spool relative to said valve body to effect corresponding movement of said tool.

7. In a metal spinning machine, the combination with a reciprocable carriage and a spinning tool mounted thereon for feeding movements crosswise of the path of travel thereof, of hydraulically-actuated piston and cylinder means

for imparting said feeding movements to said tool, said cylinder means being fixed to the carriage and said piston means being movable therein in opposite directions, means connecting said piston means to said tool for moving said tool in conformity with the movement of said piston means, a control valve movably supported on the carriage and comprising a valve body having outlet ports, an axially shiftable valve spool in said body and cooperating with said ports for controlling fluid flow therethrough, conduits connecting said outlet ports to opposite ends of said cylinder means, said spool being selectively operable in opposite directions with respect to said ports for simultaneously effecting pressure and exhaust flow therethrough and actuation of said piston means in a corresponding direction, means operatively connecting said valve body to said piston means for movement bodily therewith in the direction of movement of said spool until fluid flow is cut off, a spring for loading said valve, and means for shifting said spool relative to said valve body to effect corresponding movement of said tool, the extent of movement of said valve spool and the consequent movement of said tool being substantially the same.

8. In a metal spinning apparatus, the combination with a reciprocable carriage and a spinning tool mounted thereon for crosswise movements relative to the path of travel thereof, of a power cylinder secured to said carriage, a double acting piston positioned in said cylinder for movement toward either end thereof, means for transmitting the movements of said piston to said tool to feed it crosswise, a control valve connected to said transmitting means for movement bodily therewith and having a shiftable valve spool therein for controlling flow of fluid therethrough, said spool being selectively operable in opposite directions from a neutral position with respect to said valve for simultaneously effecting pressure and exhaust flow through the valve and movement of said piston in the same direction, whereby said valve is caused to follow the movement of said spool until flow is cut off, means for supplying inelastic fluid under pressure to said valve, a loading spring interposed between said valve and said spool for urging them in opposite directions, said valve being held motionless by fluid entrapped in said cylinder, and restraining means operatively engaging said spool for holding it quiescent in a neutral position relative to said valve, said restraining means being manually operable to effect shifting of said spool with respect to said valve and thereby cause a corresponding movement of said tool.

9. In a tube spinning machine, the combination with a spinning tool, of a carriage carrying said tool, means operable to advance and retract the carriage along a predetermined portion of the wall of a rotating blank, said tool being mounted on the carriage for movement radially of said wall, hydraulic translating means including a shiftable control member therefor disposed on said carriage and operatively connected to said tool for imparting radial movements thereto commensurate with the movement of the control member, pattern means cooperating with said shiftable member for controlling the operation of said translating means, said pattern means comprising a series of progressively contoured templets adapted to be moved one-by-one into working position for movement of said member therewith, for translation of the contours thereof into

corresponding tool movements, and means for successively bringing said templets into working position.

10. In a tube spinning machine, the combination with a spinning tool, of a carriage carrying said tool, means operable to advance and retract the carriage along a predetermined portion of the wall of a rotating blank, said tool being mounted on the carriage for movement radially of said wall, hydraulic translating means including a shiftable control member therefor disposed on said carriage and connected to said tool for moving the same radially, a rotary pattern controlling device positioned to cooperate with said shiftable member during traverse of the carriage for controlling the operation of said translating means, said device having a set of progressively contoured templets disposed around its axis and movable one-by-one into working position with respect to said control member, and indexing means for rotating said device to bring said templets successively into working position, said translating means being operative to move said tool in a path corresponding to the contour of a templet.
11. In a tube spinning machine, the combination with a spinning tool, of a carriage carrying said tool, means operable to advance and retract the carriage along a predetermined portion of the wall of a rotating blank, said tool being mounted on the carriage for movement radially of said wall, hydraulic translating means including a shiftable control member therefor disposed on said carriage and connected to said tool for moving the same radially, a rotary pattern controlling device positioned to cooperate with said shiftable member during traverse of the carriage for controlling the operation of said translating means, said device having a set of progressively contoured templets disposed around its axis and movable one-by-one into working position with respect to said control member, indexing means associated with said device, and means for automatically actuating said indexing means at each reversal of the direction of travel of the carriage, whereby the wall of said blank is progressively deformed by movement of said tool in opposite directions therealong.

12. In a tube spinning machine, the combination with a spinning tool, of a carriage carrying said tool, means operable to advance and retract the carriage along a predetermined portion of the wall of a rotating blank, said tool being mounted on the carriage for movement radially of said wall, hydraulic translating means including a shiftable control member therefor disposed on said carriage and connected to said tool for moving the same radially, a rotary pattern controlling device positioned to cooperate with said shiftable member during traverse of the carriage for controlling the operation of said translating means, said device having a set of progressively contoured templets disposed around its axis and movable one-by-one into working position with respect to said control member, indexing means for rotating said device to bring said templets successively into working position, and locking means associated with said indexing mechanism for centering and holding said templets in working position with respect to said shiftable member.

13. In apparatus for shaping tubular blanks, in combination, a rotatable chuck for gripping and rotating a blank, a spinning tool, a carriage carrying said tool, hydraulic translating mechanism including a shiftable control member therefor disposed on said carriage and operable to move

said tool radially of the wall of said blank, a rotary pattern device for controlling the operation of said mechanism, said device including an annular series of progressively contoured templets movable successively into working position to cooperate with said control member, said translating mechanism being actuated in conformity with the contour of one of said templets in said working position to effect corresponding tool movements thereby, to impart a similar shape to the wall of the blank, indexing mechanism operative to bring each of said templets into said working position, and means actuated by the carriage when it reaches either end of said pattern device for automatically actuating said indexing mechanism and effecting reversal of the direction of travel of said carriage.

14. In apparatus for shaping tubular blanks, in combination, a rotatable chuck for gripping and rotating a blank, a spinning tool, a carriage carrying said tool, hydraulic translating mechanism including a shiftable control member therefor disposed on said carriage and operable to move said tool radially of the wall of said blank, a rotary pattern device for controlling the operation of said mechanism, said device including an annular series of progressively contoured templets movable successively into working position to cooperate with said control member, said translating mechanism being actuated in conformity with the contour of one of said templets in said working position to effect corresponding tool movements thereby, to impart a similar shape to the wall of the blank, indexing mechanism operative to bring each of said templets into said working position, means actuated by the carriage when it reaches either end of said pattern device for automatically actuating said indexing mechanism and effecting reversal of the direction of travel of said carriage, and means actuated by said indexing mechanism for terminating the carriage's movement after the last templet of said series has been traversed.

15. In apparatus for shaping tubular blanks, in combination, a rotatable chuck for gripping and rotating a blank, a spinning tool, a carriage carrying said tool, hydraulic translating mechanism including a shiftable control member therefor disposed on said carriage and operable to move said tool radially of the wall of said blank, a rotary pattern device for controlling the operation of said mechanism, said device including an annular series of progressively contoured templets movable successively into working position to cooperate with said control member, said translating mechanism being actuated in conformity with the contour of one of said templets in said working position to effect corresponding tool movements thereby, to impart a similar shape to the wall of the blank, indexing mechanism operative to bring each of said templets into said working position, means actuated by the carriage when it reaches either end of said pattern device for automatically actuating said indexing mechanism and effecting reversal of the direction of travel of said carriage, and circular members disposed at the ends of said pattern device for cooperating with said control member to maintain said tool in a predetermined position with respect to the wall of said blank during indexing movement.

16. In apparatus for shaping tubular blanks, in combination, a rotatable chuck for gripping and rotating a blank, a spinning tool, a carriage carrying said tool, hydraulic translating mechanism

including a shiftable control member therefor disposed on said carriage and operable to move said tool radially of the wall of said blank, a rotary pattern device for controlling the operation of said mechanism, said device including an annular series of progressively contoured templets movable successively into working position to cooperate with said control member, said translating mechanism being actuated in conformity with the contour of one of said templets in said working position to effect corresponding tool movements thereby, to impart a similar shape to the wall of the blank, indexing mechanism operative to bring each of said templets into said working position, means actuated by the carriage when it reaches either end of said pattern device for automatically actuating said indexing mechanism and effecting reversal of the direction of travel of said carriage, means operable to control the speed of travel of said carriage, and means actuated by said indexing mechanism when a preselected templet is moved into said working position for operating said speed controlling means to reduce the rate of travel of the carriage during subsequent traverse of the said predetermined templet.

17. In apparatus for shaping tubular blanks, in combination, a rotatable chuck for gripping and rotating a blank, a spinning tool, a carriage carrying said tool, hydraulic translating mechanism including a shiftable control member therefor disposed on said carriage and operable to move said tool radially of the wall of said blank, a rotary pattern device for controlling the operation of said mechanism, said device including an annular series of progressively contoured templets movable successively into working position to cooperate with said control member, said translating mechanism being actuated in conformity with the contour of one of said templets in said working position to effect corresponding tool movements thereby, to impart a similar shape to the wall of the blank, indexing mechanism operative to bring each of said templets into said working position, means actuated by the carriage when it reaches either end of said pattern device for terminating travel thereof, means for actuating said indexing mechanism upon termination of the carriage's movement, and means responsive to completion of indexing movement for initiating carriage travel in the opposite direction.

18. Tube shaping apparatus comprising, in combination, a chuck for gripping a tubular blank at one end, means for rotating the chuck and the blank, a tool carriage encircling the peripheral wall of the blank, means for advancing and retracting the carriage along said wall, a plurality of not less than three annularly spaced spinning tools mounted on said carriage for movements radially of said wall, a movable member on the carriage, means connecting said member to each of said tools for simultaneously moving them radially, fixed cylinder means on the carriage having piston means movable therein in opposite directions and connected to said movable member to move the same, a control valve movably supported on said carriage and having a shiftable spool therein selectively movable in opposite directions from a neutral position with respect thereto, for effecting fluid flow through said valve and movement of said piston means in a corresponding direction, means connecting said member and said valve for unitary movement in the direction of movement of said spool until flow is interrupted, and means cooperating with said spool during

travel of the carriage for imparting predetermined shifting movements thereto, whereby to effect corresponding movement of said tools and radial displacement of the wall of said tube thereby.

19. A tube shaping apparatus comprising, in combination, a rotatable chuck for gripping a tubular blank at one end, a carriage movable longitudinally of the wall of said blank and having a base portion and an upright frame encircling said wall, three radial tool slides mounted on said frame in annularly spaced relation, two of the slides being disposed below the center of said base and the other slide at the top thereof, a spinning roller journalled on the inner end of each slide, an operating shaft for each slide and having a sprocket wheel thereon, rack and gear connection between each slide and its shaft, a cross slide mounted on said base portion, a driving chain meshing with said sprockets and having its ends adjustably secured to said cross slide, a power cylinder secured to the base of the carriage in a crosswise position and containing a double acting piston rigidly connected to said cross slide, a control valve mounted on said cross slide with its axis parallel to the axis of said cylinder and having an axially movable spool member, said member being selectively operable in opposite directions from a neutral position for

effecting simultaneous pressure and exhaust flow of hydraulic fluid for opposite ends of said cylinder respectively, a valve loading spring yieldably urging said member outwardly, and a templet having a contoured edge engaged by said spool member for movement therealong during travel of said carriage, whereby said spool member is shifted in conformity with the contour of said templet and corresponding radial movements are imparted to said rollers.

20. A spinning machine having, in combination, a spinning tool, means for feeding said tool alternately in opposite directions lengthwise of the wall of a rotating blank, means cooperating with said tool in both directions of lengthwise feed thereof to feed the tool crosswise of said wall and effect displacement thereof to a predetermined configuration, said last named means including a series of templates, means for moving said templates successively into position for cooperation with said tool, and control means responsive to feed movements of said tool for actuating said template moving means, whereby a successive template is moved into operative relationship with said tool at the end of each lengthwise feed stroke of the tool along said wall of the blank.

GUSTAVE J. HORAK.
